UNITED STATES PATENT OFFICE.

HAROLD S. FORSBERG, OF BRIDGEPORT, CONNECTICUT.

DESIGN FOR A HACK-SAW HANDLE.

Application filed December 8, 1925. Serial No. 15,691. Term of patent 14 years.

To all whom it may concern:

Be it known that I, HAROLD S. FORSBERG, a citizen of the United States, residing at Bridgeport, in the county of Fairfield and the State of Connecticut, have invented a new, original, and ornamental Design for a Hack-Saw Handle, of which the following

hack saw handle, showing my new design.

Fig. 2 is a top elevational view thereof;

Fig. 3 is a side elevational view of the side of hack saw handle opposite that shown

new, original, and ornamental Design for a

in Fig. 1.

I claim:

is a specification, reference being had to the accompanying drawing, forming part thereof.

Fig. 1 is a side elevational view of a
